UNITED STATES PATENT OFFICE.

BERTRANDO PANARA, OF ROME, NEW YORK.

DRYING APPARATUS.

1,242,368.

Specification of Letters Patent.

Patented Oct. 9, 1917.

Application filed April 23, 1917. Serial No. 163,906.

To all whom it may concern:

Be it known that I, BERTRANDO PANARA, a subject of the King of Italy, and resident of Rome, county of Oneida, and State of New York, have invented certain new and useful Improvements in Drying Apparatus, of which the following is a specification.

This invention relates to drying apparatus and more particularly to macaroni driers.

It is one of the objects of the invention to provide a drier that will be simple and of compact construction, and adapted for continuous operation.

Another object is to provide a drier that will be capable of operation in an efficient manner with a minimum production of scrap or waste.

Other objects and the features of novelty will be apparent from the following description taken in connection with the accompanying drawings in which:

Figure 1 is a partial side elevation and partial longitudinal section of a drier embodying the invention; and

Fig. 2 is a transverse section of the line 2—2 of Fig. 1.

Referring to the drawings 10 indicates a tier of rectangular rooms and 11 a second tier arranged on the tier 10 and with its rooms directly over the rooms of the tier 10 and adapted to be shut off therefrom by removable partitions 12. It will be understood that there may be other tiers above the tier 11 and the rooms of each tier separated from those of the adjoining tiers by removable partitions similar to the partitions 12. The rooms of each tier are separated by vertical partitions 13 and have doors 14 on one or two sides. Each of the rooms is also provided with supports 15 for poles 16 on which the macaroni 17 is hung.

Above the tier 11 is a chamber 18 in which there is arranged a ventilating fan 19 on shaft 20, the latter being driven by power in any suitable manner, as by pulley 21.

The rooms of the tier 11 are separated from the chamber 18 by removable partitions 22 and to give convenient access to these partitions the chamber 18 may be provided with doors 23 on one side. Air may

be supplied to chamber 18 through openings 24 in the end walls or in any other suitable manner.

55

In the operation of the drier the rotation of fan 19 causes a circulation of air downwardly through the rooms. When used in connection with a continuously operating macaroni plant some of the rooms will be 60 in process of filling with fresh macaroni and others in process of being emptied at all times. All rooms in which the macaroni is drying will be open to chamber 18, the partition 22 being out. The doors 14 on 65 one or both sides of the room will be open to permit the air, which flows downwardly from chamber 18 to escape. When it is desired to dry macaroni in a room of tier 10 the partition 12 is removed and the doors 70 14 of the room opened. In that event the doors of the room above may be open or closed.

The drier will be housed in a suitable building provided with any well known 75 form of ventilating system.

Having thus described my invention what I claim is:

1. In apparatus of the class described, the combination of a plurality of tiers of 80 separate drying rooms, doors on one or more sides of said rooms, a ventilating chamber above said tiers, a fan for blowing air from said chamber into the rooms of the uppermost of said tiers, means for shutting off 85 any of the rooms of said uppermost tier from said chamber, and means for separately closing off the rooms of one tier from the rooms of another tier.

2. In apparatus of the class described, 90 the combination of a plurality of tiers of separate drying rooms, doors on one or more sides of said rooms, a ventilating chamber above said tiers, a shaft extending longitudinally of said chamber, fans on said shaft 95 adapted to circulate the air from said chamber to the rooms therebelow, means for shutting off any of the rooms of said uppermost tier from said chamber, and means for separately closing off the rooms of one tier from 100 the rooms of another tier.

In testimony whereof I affix my signature.

BERTRANDO PANARA.
